BURIAL CASKET

Walter K. Nelson, Pittsburgh, Pa., assignor to National Casket Company, Boston, Mass., a corporation of New York

Filed Mar. 5, 1962, Ser. No. 69,096

Term of patent 14 years

(Cl. D19—1)

The FIGURE is a perspective view of a burial casket showing my new design. The side and end, not shown, are substantially identical to the side and end shown, and the bottom is plain and unornamented.

I claim:

The ornamental design for a burial casket, as shown and described.
